UNITED STATES PATENT OFFICE.

SABE G. GIST, OF STOCKTON, CALIFORNIA.

AWNNG CONSTRUCTION.

Application filed March 9, 1926. Serial No. 93,370.

This invention relates to improvements in awnings for windows of all kinds, but is especially adapted for use on the windows of modern office buildings and the like.

5 The principal object of my invention is to provide an awning and supporting elements therefor, so arranged that the awning is drawn sideways to fold or clear the same from the window instead of being hoisted vertically as is now done.

This arrangement has several valuable features. In the first place it may be adjusted so as to shut off only the direct rays of sun, wherever they may be, from penetrating 15 through the window. This allows the light to enter the room from the top to the bottom of the window over that portion thereof not in direct line with the sun's rays. This is contrary to what is possible with the ordinary awnings. With the latter if the sun shines horizontally through the window only at one corner thereof, the awning must be let down all the way, practically darkening 20 the entire room. This is not necessarily desired; since while direct glare is to be avoided the occupants usually want good daylight in the room. If the completely shaded or semi-dark features are wanted however 25 they can as easily be obtained with my awnings as with the others.

Another valuable feature of my arrangement is that the awning when closed up or folded remains in straight vertical folds. Dirt, water and other matter from above 30 cannot therefore collect in the creases of the awning, and as a result it wears much longer than the ordinary kind.

Further, it is then (in office buildings and the like) concealed inwardly of the overhanging of the wall around the window casing. This protects the awning and burning 40 matches, cigarette stubs and the like cannot fall on the awning from above and start fires, such as frequently occur with the present construction.

The awnings being, as above stated, protected from deterioration and damage, it is not necessary to take them down at the end 45 of the season, thus eliminating the work incident to constantly removing and replacing the awnings.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

60 In the drawings similar characters of reference indicate corresponding parts in the several views:

Fig. 1 is a perspective view of an awning in place, showing its appearance from outside the window when completely opened or spread.

Fig. 2 is a similar view with the awning partly folded.

Fig. 3 is a sectional plan on the line 3—3 70 of Fig. 2.

Fig. 4 is a vertical section of the awning.

Fig. 5 is a fragmentary view of the lower supporting member showing the connection 75 of the awning therewith.

Referring now more particularly to the characters of reference on the drawings, the numeral 1 denotes the upper horizontal supporting member, a straight bar which extends across the window casing 2 at the top and outwardly of the same and in spaced relation thereto. If the wall 3 of the building overhangs the casing, as is always the case in modern office buildings, this bar is inwardly of the outer edge of the wall, as 80 shown in Fig. 3.

The lower supporting element 4 is a horizontal bar having an outward curvature of suitable contour from end to end. This bar is pivotally mounted at its ends on brackets 90 5 secured to the sides of the casing 2 a certain distance from the bottom of the same.

Extending between the bars and from end to end of the same is an awning 6, of usual material and cut to have a smooth fit when 95 fully spread as shown in Fig. 1. This awning is supported by the bars by means of grommets 7 secured to the awning and slidably embracing said bars.

One vertical edge of the awning is preferably secured to the adjacent side of the window casing by suitable means, but the other edge is free and has a stiffening rod extending from top to bottom of the same.

A pull-cord 9 is connected to said rod 105 about half way up, said cord extending thence horizontally around a swivel pulley 10 attached to the corresponding side of the casing, and to a cleat 11 within easy reach of the occupants of the room.

110 Attached to the rod at the same point as the connection of the cord 9 therewith is

another cord 12 or the like, which extends thence horizontally to a spring controlled roll or winding drum 13 of common form which is fixed on the casing 2 on the opposite side thereof from the pulley 10.

If the cord 9 is pulled the awning will therefore be moved along the supporting bars against the resistance of the spring drum 13, the cord 12 being then unwound.

10 The awning may thus be fully spread or held at any desired point along the bars by raising the end of the cord 9 about the cleat. When said cord is released the cord 12 will pull the awning in the opposite direction to 15 a full folded position if allowed to do so. In this case the awning is then entirely at one end of the supporting bars and is folded, with vertical folds, only, in a compact space under the overhang of the wall 3. 20 Therefore the awning is completely protected from exposure to articles dropping from above, and no dirt, water or other matter will rest or collect in the folds.

25 The distance between the bars at their ends is of course less than the distance between the bars at other points, owing to the outward curvature of the lower bar, while the other is straight throughout. Since the awning, when fully spread, has a snug and taut fit, the movable end edge is of course shorter than the awning at the center, and the same is true in gradually lessening degrees at all 30 intermediate points.

35 The lower bar is therefore hinged at its ends as previously stated, so that the short edge of the awning, when moving along the bars, will cause the lower bar to swing up to allow the awning to thus move without its being stretched or without bending the bars.

40 Though I have shown spring means to fold the awning, this may be omitted, and the movement of the awning in both directions controlled by hand actuating rods.

45 In installing the awning in any window, the path of movement of the sun relative to

such window should be noted and the fixed edge of the awning accordingly located along that edge of the window casing most often in line with the direct rays of the sun.

From the foregoing description it will be 50 readily seen that I have produced such a device as substantially fulfills the objects of the invention as set forth herein.

While this specification sets forth in detail the present and preferred construction 55 of the device, still in practice such deviations from such detail may be resorted to as do not form a departure from the spirit of the invention, as defined by the appended 60 claims.

Having thus described my invention what I claim as new and useful and desire to secure by Letters Patent is:

1. An awning structure comprising upper and lower supporting bars horizontally disposed, and adapted to be mounted onto a window casing; the lower bar having a convex curvature relative to the window, an awning extending between and slidably mounted on the bars for folding movement 65 lengthwise thereof, means for controlling such movement, and means for pivotally mounting the lower bar at its ends for vertical swinging movement.

2. An awning structure comprising upper and lower supporting bars horizontally disposed, and adapted to be mounted onto a window casing; the upper bar being straight and the lower bar having a convex curvature relative to the window, and the end of 75 both bars being in substantially common vertical alignment, an awning extending between and from end to end of the bars and slidably therealong, and means whereby the awning may be moved from one end lengthwise along the bars without stretching the awning or bending the bars.

80 In testimony whereof I affix my signature.

SABE G. GIST.
